St. Louis

George J. Haller of Buffalo, N.Y.

Letters Patent No. 2159-Dated Aug. 8-1865.

Design for a Bust of Abraham Lincoln.

The schedule referred to in these Letters Patent and making part of the same.

Wall whom it may concern:

Be it known that George J. Haller, of the City of Buffalo, in the County of Erie and State of New York, have originated a new design for a Bust of Abraham Lincoln, late President of the United States, of which the following is a full, clear & exact description thereof, reference being had to the accompanying photographic representation part of this specification.

My design and invention consists in draping or enveloping the lower portions of the bust, with the National flag of the United States, by entwining the same in a loosely convoluted form around the shoulders and back, and obliquely from the left shoulder down across the breast in such a manner that the stars shall be exhibited on the right shoulder and the stripes on the left and in front substantially as represented.

The design is intended to symbolize and commemorate in this most appropriate manner the intimate relations which existed between government and the late and unfortunate President, and to perpetuate the memory of his martyrdom, and those virtues that have embalmed him in the hearts of his countrymen.

What I claim as my invention and desire to secure by Letters Patent, is the design of the bust substantially as set forth.

In witness whereof I have hereunto signed my name in the presence of two subscribing witnesses.

Witnesses:

Jay Ryatt
J. F. Fraser

Geo. J. Haller.
